UNITED STATES PATENT OFFICE.

WILLIAM HARRY STONE, OF LOS ANGELES, CALIFORNIA.

APPARATUS FOR OPERATING FUMIGATING-TENTS.

1,295,079.

Specification of Letters Patent. Patented Feb. 18, 1919.

Application filed July 22, 1918. Serial No. 246,235.

To all whom it may concern:

Be it known that I, WILLIAM HARRY STONE, a citizen of the United States, residing at Los Angeles, in the county of Los Angeles and State of California, have invented new, and useful Improvements in Apparatus for Operating Fumigating-Tents, of which the following is a specification.

10 My object is to make an apparatus for operating fumigating tents, and my invention consists of the novel features herein shown, described and claimed.

Figure 1 is a side elevation showing an apparatus for operating fumigating tents embodying the principles of my invention and in operation in connection with the fumigating tents.

Fig. 2 is a top plan view of the truck and operating mechanism, the arms and tents being omitted.

Fig. 3 is an enlarged fragmentary side elevation looking in the direction indicated by the arrow 3 in Figs. 1 and 2.

25 Fig. 4 is a fragmentary top plan view looking in the direction indicated by the arrow 4 in Fig. 1 and showing the details of the arms, the trucks being omitted.

Fig. 5 is a diagrammatic view of a hoisting mechanism.

The rigid main frame 1 is mounted upon a rigid rear axle 2, the axle 2 is mounted upon rear wheels 3, the frame 1 is mounted upon the front axle 4 and connected thereto by a rocker and kingbolt construction 5, and a draft rigging 6 is connected to the axle 4; so as to produce a truck on the order of a farm wagon and which may be moved through an orchard from tree to tree.

40 A turn table 7 is mounted upon the rigid frame 1 and held in place by a central kingbolt construction 8. Masts 9 and 10 extend upwardly from the intermediate portions of the turn table 7, and braces 11 and 12 connect the masts 9 and 10 to the outer portions of the turn table 7, so as to hold the masts 9 and 10 in vertical parallel positions. The arms 13 and 14 are pivotally mounted between the upper ends of the masts 9 and

45 10 by a pin 15, there being a plurality of mating openings 16 through the masts 9 and 10, so that the pin 15 may be raised or lowered by moving it from one pair of openings 16 to another. The arms 13 and 14 are 50 substantially alike and are crossed like a pair of shears. The arm 13 comprises side

bars 17 and 18 spaced apart at their inner lower ends by braces 19 and secured together at their outer ends by a bolt 20. In a like manner the arm 14 comprises the side bars 60 21 and 22 spaced apart at their inner lower ends by braces 23 and secured together at their outer ends by a bolt 24.

In mounting the arms 13 and 14 upon the pin 15 the side bar 21 may be placed inside 65 of the side bar 17 and the side bar 18 inside of the side bar 22 and a spacing collar 25 may be placed upon the pin 15 between side bars 18 and 21. A cross bar 26 is rigidly mounted between the extreme lower ends of 70 the side bars 21 and 22 and a similar cross bar 27 is rigidly mounted between the lower ends of the side bars 17 and 18.

Links 28 and 29 are connected to the cross bars 26 and 27 and the lower ends of the 75 links 28 and 29 are connected together by a pivot 30. The pulley 31 has a hook 31' and a hook 31' engages the spacing collar 25 so that the pulley 31 is supported by the pin 15. A windlass construction 32 is 80 mounted upon the platform 7 and extends below the lower ends of the masts 9 and 10. A cable 33 is attached to the pivot 30 and extends over the pulley 31 downwardly under the pulley 33' around the windlass 32 85 and upwardly and is again attached to the pivot 30, so that when the windlass 32 is operated the arms 13 and 14 may be raised or lowered so that the pivot 30 is held both ways. 90

Links 34 and 35 are connected to the upper outer ends of the arms 13 and 14 by pins 36 and 37, there being a series of holes 38 and 39 through the arms so that the pins may be moved from one hole to another to 95 vary the effective lengths of the arms, and the links 34 and 35 consist of two parallel straps spaced apart by the thickness of the arm, and pins 40 and 41 connect the lower ends of the straps, there being spacing collars or guide rollers upon the pins between the straps. The tents 42 and 43 are connected to the links 34 and 35 by cords 44 and 45, the said tents 42 and 43 being large enough to cover the trees to be fumigated. 100 Semi-circular hoops 46 and 47 are connected to the lower edges of the tents 42 and 43 and the hoops are located at the outer sides of the tents from the truck. A rope or cable 48 is connected to the cord 44 and extends 105 downwardly under a pulley 49, said pulley being attached to the hook 46, and the rope

extends upwardly over the pin 40, then over the pulley 50 and downwardly to the fastening 51. In a like manner the rope or cable 52 is attached to the cord 45 and extends 5 downwardly around the pulley 53 attached to the hook 47 and upwardly over the pin 41 and over the pulley 54 and downwardly to the fastening 55. The pulley 50 is mounted upon the mast 10 and the pulley 54 is mounted 10 upon the mast 9.

In the practical operation the truck is moved between the rows of trees. The ropes 48 and 52 are manipulated to hold the tents 42 and 43 upwardly and then the windlass 15 32 is operated to swing the arms 13 and 14 upwardly until the machine is located in proper relation to two trees. Then the device is manipulated and the tents dropped around the trees to the ground as shown in 20 Fig. 1. After the fumigating operation has been completed, the ropes 48 and 52 are pulled to raise the outer central portions of the hoops 46 and 47 as much as is practical. Then the windlass 32 is operated to raise the 25 tents bodily from the trees and then the truck is moved to operative position relative to the next two trees.

When the tents 42 and 43 are to be operated in this way they may be made imperforate from their lower edges up and all the 30 way around, whereas tents operated by hand are usually made with flaps to be buttoned together, and such tents will waste more or less of the fumigating gas.

35 Various changes may be made without departing from the spirit of my invention as claimed.

I claim:

1. An apparatus for operating fumigating tents comprising a truck, masts mounted 40 upon the truck, arms pivotally mounted upon the masts, said arms being crossed, a windlass connected to the inner lower ends of the arms, tents connected to the outer 45 ends of the arms, means connected to the outer

lower edges of the tents for holding said edges in extended position, and ropes connected to the hoops and extending over guide means to the truck.

2. An apparatus for operating fumigating tents comprising a truck, a turn table mounted upon the truck, a mast mounted upon the turn table, arms pivotally mounted upon the mast, links adjustably connected to the outer ends of the arms, tents connected 50 to said links, each tent having connected thereto at its lower outer end a semi-circular hoop, a flexible connection from said hoops passing to the lower ends of said links to the mast, and means for simultaneously lifting or lowering said arms.

3. An apparatus for operating fumigating tents comprising a truck, a mast mounted thereon, an arm pivoted thereto, a link adjustably connected to the outer end of said arm, a tent suspended from the lower end of said link, the outer lower edges of the tent remote from said truck being provided with a hoop, flexible means connected to said link and to said mast for independently raising 60 said hoop and the side of the tent remote from the truck independently of the other side of the tent, and means for raising or lowering said arm.

4. An apparatus for operating fumigating tents comprising a truck, a mast mounted thereon, an arm pivoted thereto, a link adjustably connected to the outer end of said arm, a tent suspended from the lower end of said link, the outer lower edges of the tent 70 remote from said truck being provided with a hoop, flexible means connected to said hoop and to said mast for independently raising said hoop and the side of the tent remote from the truck independently of the other side of the tent, and means for raising or lowering said arm.

In testimony whereof I have signed my name to this specification.

WILLIAM HARRY STONE.

Copies of this patent may be obtained for five cents each, by addressing the "Commissioner of Patents, Washington, D. C."
